ROLLER SKATE UNIT AND ROLLER SKATE SHOE

Michael Goldenberg, Philadelphia, Pa.

Application January 30, 1940, Serial No. 316,397

6 Claims. (CL 36—1)

This invention relates to roller skate units comprising a shoe and a roller skate attached thereto, and has as its object the production of a new and improved roller skate unit.

This invention relates further to shoes which are to be used in combination with roller skates, and has as its further object the production of a new and improved shoe of this type.

This invention relates further to braking means (commonly called "stop-quicks") for roller skate units and shoes which are to be used in combination with roller skates, and has as its still further object the production of a new stop-quick.

Stop-quicks now in common use are merely extra thicknesses of leather, or the equivalent, which are attached by nails to the toe end of the sole of the shoe. These stop-quicks are objectionable because the nails by which they are attached damage the skating rink floor. For this reason, skating rink proprietors generally forbid their use in spite of their usefulness to the skater. These stop-quicks are further objectionable because they are not readily replaceable in spite of the fact that they are subject to heavy duty and rapidly wear out. It is therefore necessary to send the shoes to the shoemaker each time that the stop-quicks now in common use must be replaced. A further deterrent to the use of stop-quicks from the skater's point of view is the high cost of shoe maintenance resulting directly from said use. For the strain upon the sole of the shoe incident to the use of a stop-quick often causes the sole to be torn away from the upper.

It is one of the objects of this invention to produce a roller skate unit with a stop-quick which will not mar the skating rink floor and which will be readily replaceable.

Another of the objects of this invention is to produce a shoe which is to be used in combination with a roller skate or as part of a roller skate unit which will have as a component part thereof a stop-quick which will not mar the skating rink floor and which will be readily replaceable.

Still another of the objects of this invention is to produce a stop-quick which will not mar the skating rink floor, which will be readily replaceable and which will be comparatively inexpensive.

Still another of the objects of this invention is to produce a shoe for use in combination with a roller skate or a part of a roller skate unit

which will withstand the strain incident to the use of a stop-quick.

I attain the foregoing as well as other objects by forming a knob-like member of suitable material, such as rubber or leather, by providing this member and the toe end of the sole of the shoe with cooperating means which serve to detachably attach the knob-like member to the toe end of the sole of the shoe, and by reinforcing the connection between the shoe sole and shoe upper in the fore part of the sole.

For the purpose of illustrating my invention with the particularity required by law, I have shown in the drawings which form a part hereof, and will now describe, two of the many possible forms into which my inventive concepts may be embodied.

In said drawings,

Figure 1 is a perspective view of my novel roller skate unit. A portion of the shoe top has been broken away to permit the showing of the novel elements on as large a scale as possible.

Figure 2 is a bottom view of the roller skate unit shown in Figure 1. A portion of the skate has been broken away to show otherwise hidden parts.

Figure 3 is a section taken on the line 3—3 of Figure 1.

Figure 7 is a perspective view of the male plate fastening element which is imbedded in the stop-quick shown in Figures 1 to 3.

Figure 4 is a perspective view of a modification of the novel roller skate unit shown in Figure 1. A portion of the shoe top has been broken away for the purpose of showing the novel elements on as large a scale as possible. Portions of the skate tread have been broken away to show an otherwise hidden part.

Figure 5 is a bottom view of the roller skate unit shown in Figure 4. Portions of the skate have been broken away to show otherwise hidden parts.

Figure 6 is a section on the line 6—6 of Figure 5.

Figure 8 is a perspective view of the female fastening plate which is embedded in the stop-quick shown in Figures 4 to 6.

Referring more particularly to the drawings wherein similar reference numerals denote similar parts, reference numeral 1 designates my novel roller skate unit shown in Figures 1 to 3. The roller skate unit 1 comprises the shoe member 2, the roller skate member 3, and the stop-quick member 4 which is detachably attached to the sole 6 of the shoe member 2.

The shoe member 2 differs in the following particulars from the shoe members now in use in roller skate units or in connection with roller skates:

(a) The upper 8 is attached to the fore part 7 of the shoe sole 6 by two lines of stitching 9 and 9 spaced from each other instead of the customary single line 8.

(b) The fore part 7 of the shoe-sole 6 has anchored therein near the toe end 10 thereof an internally threaded tubular rivet 11, which serves as the female element of the cooperating fastening means which serves to detachably attach the stop-quick member 4 to the shoe member 2.

The roller skate member 3 is exactly the same as the roller skate members now in use in roller skate units and for that reason will not be here further described. It may be fixedly attached to the shoe by means of rivets in the manner well known in the art or it may be detachably attached to the shoe. The skate shown in Figures 1 to 6 is fixedly attached to the shoe by rivets 38.

The stop-quick member 4 consists of a rubber body member 12 which has embedded therein near the lower face 13 thereof the male plate fastening element 14. The male plate fastening element 14 consists of the inverse saucer-like plate 15 which has formed therein the apertures 16 and which has extending therefrom from the face 17 thereof the threaded finger 18. The plate 15 is made preferably of resilient material and is preferably curved as shown in Figure 3 in order to give it the maximum strength to resist the strains which are put upon it when the stop-quick is being used by the skater and to more securely anchor the male plate fastening element 14 in the rubber body member 12 of the stop-quick 4. The apertures 16 serve to more securely anchor the male fastening plate 14 within the rubber body member 12 since the rubber extends through the apertures 16 when the stop-quick is being molded. The threaded finger 18 is received within and its threads cooperatively engage the threads formed in the tubular rivet 11 and serves as the male element of the cooperating fastening means which serves to detachably attach the stop-quick member 4 to the shoe member 2. The lower face 13 of the rubber body member 12 is preferably curved upwardly as shown in Figure 3 in order to permit the body member 12 to more firmly adhere to the surface 19 of the sole 6. The lower face 13 of the body member 12 is preferably curved upwardly as shown in Figure 3 for the further reason that such a structure imparts greater resiliency to the body member 12 in yielding to the stresses imposed upon it when the stop-quick is in use. This in turn decreases the strain on the shoe when the stop-quick is used.

The roller skate unit 20 shown in Figures 4 to 6 differs from that shown in Figures 1 to 3 only in the following particulars:

(a) The shoe member 21 differs from the shoe member 2 in the fact that rivets 22 have been substituted for the line of stitches 8, in the fact that the externally threaded rivet 23 has been substituted for the tubular rivet 11, and in the fact that a circular groove 25 has been formed in the sole 24 of the shoe member 21 at the point where the rivet 22 extends therethrough. The externally threaded rivet 23 functions as the male element of the cooperating fastening means which serves to detachably attach the stop-quick 26 to the shoe sole 24.

(b) The stop-quick 26 differs from the stop-quick 4 in the fact that the female plate fasten-

ing element 27 has been substituted for the male plate fastening element 14 and in the fact that the sides 34 of its body member 32 are substantially at right angles to the plane of the face 33, whereas the sides 36 of the body member 12 of the stop-quick 4 form an obtuse angle with the plane of the face 31 of said body member 12. The female fastening plate element 27 differs from the male fastening plate element 14 only in the fact that the internally threaded tubular finger 28 has been substituted for the externally threaded solid finger 18. The threaded aperture 29 of the internally threaded finger 28 receives the threaded rivet 23 and functions as the female element of the cooperating attaching means which serves to detachably attach the stop-quick member 26 to the shoe sole 24. The circular groove 25 functions to form an air pocket under the internally threaded tubular finger 28 and permits said internally threaded tubular finger to move downwardly when such movement becomes necessary as a result of the forces set up when the stop-quick is in use. This increases the resiliency of the stop-quick which in turn decreases the stress on the shoe when the stop-quick is used. It is to be noted that the plate 30 of the female plate fastening element 27 is exactly the same in structure and function as the plate 15 of the male plate fastening element 14, that the apertures 31 of said element 27 are exactly the same in structure and function as the apertures 16 in said element 15. It is further to be noted that although the body member 32 of the stop-quick 26 is slightly different in structure from the body member 12 of the stop-quick 4 nevertheless it has the same function as said body member 12 with the face 33 of the body member 32 being curved upwardly and having the same function as the face 13 of said body member 12.

40 The foregoing disclosure is to be understood as being for the purpose of illustration only and not for the purpose of limitation, since many changes may be made in the devices here shown without departing from the spirit of my invention. 45 These changes may include changes in the material of which the elements here shown are made and the substitution of equivalents for each and every one of said elements.

Having described my invention, what I claim as new and useful is:

1. A stop-quick for detachable attachment to the toe of the sole of a shoe to which a roller skate is to be attached and said sole having attached thereto near said toe one of the elements of a detachable fastening means, said stop-quick comprising a body member; a plate which is curved upwardly relatively to the plane of the outer face of said sole imbedded in said body member near the lower face thereof; and an element of said detachable fastening means carried by said plate and extending from said plate through and beyond the lower face of said body member, said element being that element of said detachable fastening means which is to cooperatively engage that element of said detachable fastening means carried by said sole.

2. A stop-quick for detachable attachment to the toe of the sole of a shoe to which a roller skate is to be attached and said sole having attached thereto near said toe one of the detachable elements of a fastening means, said stop-quick comprising a body member the lower face of which is curved upwardly relatively to the plane of the outer face of said sole; a plate which is curved upwardly relatively to the plane of the

outer face of said sole imbedded in said body member near the lower face thereof; and an element of said detachable fastening means carried by said plate and extending from said plate through and beyond the lower face of said body member, said element being that element of said detachable fastening means which is to cooperatively engage that element of said detachable fastening means carried by said sole.

3. A stop-quick for detachable attachment to the toe of the sole of a shoe to which a roller skate is to be attached, said sole having attached thereto near said toe the female element of a detachable fastening means, said stop-quick comprising a body member; a plate which is curved upwardly relatively to the plane of the outer face of said sole imbedded in said body member near the lower face thereof; and the male element of said detachable fastening means carried by said plate and extending from said plate through and beyond the lower face of said body member.

4. A stop-quick for detachable attachment to the toe of the sole of a shoe to which a roller skate is to be attached, said sole having attached thereto near said toe the male element of a detachable fastening means, said stop-quick comprising a body member the lower face of which is curved upwardly relatively to the plane of the outer face of said sole; a plate which is curved upwardly relatively to the plane of the outer face of said sole imbedded in said body member near the lower face thereof; and

the female element of said detachable fastening means carried by said plate and extending from said plate through and beyond the lower face of said body member.

5. A stop-quick for detachable attachment to the toe of the sole of a shoe to which a roller skate is to be attached, said sole having attached thereto near said toe the male element of a detachable fastening means, said stop-quick comprising a body member; a plate which is curved upwardly relatively to the plane of the outer face of said sole imbedded in said body member near the lower face thereof; and the female of said detachable fastening means carried by said plate and extending from said plate through and beyond the lower face of said body member.

6. A stop-quick for detachable attachment to the toe of the sole of a shoe to which a roller skate is to be attached, said sole having attached thereto near said toe the female element of a detachable fastening means, said stop-quick comprising a body member the lower face of which is curved upwardly relatively to the plane of the outer face of said sole; a plate which is curved upwardly relatively to the plane of the outer face of said sole imbedded in said body member near the lower face thereof; and the male element of said detachable fastening means carried by said plate and extending from said plate through and beyond the lower face of said body member.

MICHAEL GOLDENBERG.
